DIESEL ENGINE COMPANY, OF ST. LOUIS, MISSOURI, A CORPORATION OF MISSOURI.

ENGINE-COOLING SYSTEM.

1,425,151.

Specification of Letters Patent. Patented Aug. 8, 1922.

Application filed February 10, 1918. Serial No. 142,721.

To all whom it may concern:

Be it known that I, HUBERT C. VERHEY, citizen of Holland, residing in St. Louis, Missouri, have invented the following described Improvements in Engine-Cooling Systems.

The invention relates to cooling and lubricating systems for internal combustion engines. It comprises particularly certain improvements in respect to the means of cooling of the piston and the piston-pin bearing, whereby a desirable construction and an effective utilization of the cooling liquid are obtained. It also provides in conjunction with the cooling system advantageous means for indicating the thermal condition of the bearings of the respective engine cylinders. These and other features and objects will be apparent to those skilled in the art as the specification proceeds and from a consideration of the annexed drawings, wherein:

Fig. 1 is fragmentary vertical section through one of the engine cylinders, showing parts of the engine in elevation, the plane of the section being parallel with the axis of the crank-shaft;

Fig. 2 is a vertical section on a smaller scale taken at right angles to the crank-shaft; and

Fig. 3 is a partial side elevation of the engine.

The engine cylinders 2 are supported upon columns 3 rising from the base, the intervening space being enclosed by suitable wall members 4 and 5 forming the crank case.

The piston 6 in each cylinder is constructed with a closed chamber 7 beneath its top wall for the circulation of cooling liquid, this space being shown as accessible from the bottom through an opening closed by a bolted plate 8. The piston-pin 9 fixed at its ends in cross sockets in the sides of the trunk of the piston affords the bearing for the upper end of the connecting rod 10, the lower end being connected as usual with the crank of the crank-shaft 11.

The piston-pin is also hollow for the circulation of the cooling fluid in order to cool the connecting rod bearing, this being accomplished by forming the pin with a through-bore 12 of substantial proportions, the ends of which are closed by the solid ends 14 and 15 of a screwed-in plug 16 or otherwise. In its intermediate and major portion the said plug is reduced as shown

so as to provide a horizontal, longitudinal partition 17, constituting a baffle for causing the liquid to pursue a circuitous course through the pin. The webs 18 integral with the partition baffle and the plug ends center 19 the structure in the bore.

Telescopic connections are provided for connecting the interior of the piston and its piston pin with the external parts of the circulatory system. The cooling liquid, which is preferably oil, is supplied from a pump or other suitable source not shown, through a header pipe 20, from which extend, in multiple relation, a plurality of branches 21, one for each cylinder of the engine. In this instance each branch delivers oil first to the curved space 22 in the lower part of one of the crank-shaft bearings 23, whence it passes upward through piping 24 to a connection 25 on a drip guard 26 located over the crank. From this connection a tube 27 constituting the stationary member of one of the telescopic connections projects upward into the piston. For the return of the liquid another stationary tube 28 is similarly mounted upon a connection 25 on the drip guard at the opposite side of the connecting-rod. From this and the other corresponding connections the respective return line branches 29 pass to inlets at the upper ends of the eight chambers of a row of indicators 30 conveniently located upon the outside of the crank case walls 5, the branches being continued by pipes 31 leading from outlets 32 at the bottoms of said chambers to a return header 33.

The lower ends of the stationary tubes 27 and 28 may be flexibly jointed to their supports as indicated, and their upper portions are guided in tubular members 39 and 40 projecting downward from longitudinal openings in side pillars 41 of the piston, wherein the said tubular members are screwed as shown at 42 and locked by set-screws 43. Stuffing-boxes 44 are provided at the junction to make the sliding joints tight.

The openings wherein the tubes 39 and 40 are secured are extended upward through the piston-pin 9, itself, and the portions of the pillars 41 above the piston-pin into the piston chamber 7. Tubes 45 and 46 standing in these upper openings, and preferably screwed at their lower ends into the members 39 and 40, of which they may be regarded as extensions, receive the upper ends 47

of the stationary tubes 27 and 28. The inlet tube 45, it will be observed, is tightly fitted in the portion of its opening which passes through the partition 17, beneath which it is provided with one or more lateral ports 47 establishing communication with that part of the interior cavity of the piston-pin which lies beneath the partition, while the portion of the opening leading upward from the top of the piston-pin chamber is larger than the tube, so as to afford an annular passage 48, through which the liquid flows upwardly into the piston cooling chamber. An opening 49 through the end of the partition remote from the inlet tubes enables the liquid to pass from the lower to the upper part of the piston-pin space and thus reach the passage 48 and the upper end of the tube 45 is closed to constrain the flow to take place in the manner indicated, though manifestly a certain amount of direct flow into the said chamber might be permitted through a sufficiently restricted exit without unduly lowering the circulation through the piston-pin. The annular passage 48 and a similar space 48^a around the lower part of the tube 45 affords access of the fluid to the outside of the piston-pin, whence by seepage or through the provision of suitable ducts it may reach the bearing surfaces, from which it is withdrawn through an opening 51 in the bush bearing 52 into a longitudinal channel 53 in the connecting-rod, finally escaping through ducts in the crank-shaft which are of familiar character and therefore not illustrated, into piping 54, which may return this portion of the liquid to the general source of supply and thus back into circulation.

The liquid which emerges from the upper end of the annular passage 48 enters the lower part of the piston cavity, while the exit therefrom through the open upper end 45 of the tube 46 is adjacent the top of the cavity. An annular passage 55 around this tube, between the same and the encircling wall of the opening wherein it stands affords further access of liquid to the piston-pin bearing for lubricating purposes. The portion of this opening which intersects the piston-pin is defined by a short tube 56, which is tightly seated at its ends in the top and bottom of the pin, and which prevents escape of liquid at this point from the interior.

The indicators 36 heretofore referred to are constructed to receive a removable thermometer 57 or other heat-responsive device, which may be inserted to ascertain the temperature of the liquid passing through the respective branches of the cooling system. In this way a substantial check may be kept upon the condition of the bearings, and more particularly of the piston-pin

bearing, where trouble is most likely to occur without other immediate indication, and to produce a noticeable rise in the temperature of the cooling fluid. In addition to the readings obtainable with the thermometer a serviceable indication of the condition of the liquid, and consequently of the bearings, is afforded by the sight-glasses 58 with which the fronts of the chambers are equipped and through which an oil mist, such as would be produced by a degree of heating of the liquid corresponding to a serious condition of the bearing is readily observable.

What is claimed as new is:

1. In an internal combustion engine, the combination with a piston containing a cooling space, a piston-pin mounted in the piston, and a crank-shaft bearing, of a cooling system organized to circulate liquid successively in cooling relation to the crank-shaft bearing, the piston-pin and through the interior of the piston. 80
2. In an internal combustion engine, means for cooling the piston-pin bearing, comprising a hollow piston-pin included in the circulating system of a cooling medium, and a baffle wall in said pin establishing flow in two directions within said pin. 85
3. In an internal combustion engine, means for cooling the piston-pin bearing, comprising a piston-pin having an interior cavity with entrance and exit for cooling liquid, and a longitudinal partition for producing a circuitous flow of the liquid 100 therein. 95
4. In an internal combustion engine, means for cooling the piston-pin bearing, comprising a piston-pin formed with a bore providing a cooling chamber, an end closure 105 for the bore, and a baffle in the chamber connected with the end closure. 105
5. In an internal combustion engine, means for cooling the piston-pin bearing, comprising a piston-pin formed with a bore 110 providing a cooling chamber, a plug closing the opposite ends of the bore and having its intermediate portion reduced to form a baffle structure. 115
6. In an engine cooling system a piston containing a cooling chamber, a piston-pin, and a telescopic connection with the exterior portion of the cooling system including one or more tube members intersecting the piston-pin and projecting into 120 the interior of the piston. 120
7. In an internal combustion engine, a piston and piston-pin cooling system including the combination of a piston containing a cooling chamber, a hollow piston-pin, and a 125 telescopic connection with the exterior portion of the cooling system including a tube member carried by the piston, projecting into and closed to direct communication with the piston chamber, and laterally com- 130

1 municating with the interior of the piston-pin, and a passage connecting said interior of the piston pin with the piston chamber.

8. In an internal combustion engine, the 5 combination of a piston having a cooling chamber, a hollow piston-pin, a closed-end tube carried by the piston and passing through the pin into said chamber and having a lateral opening communicating with 10 the interior of the pin, a stationary tube telescopically entering said closed-end tube, a passage in the piston between the interior of the pin and the cooling chamber of the piston, and telescopic connections to said 15 chamber.

9. In an engine cooling system the combination of a piston containing a cooling chamber, a hollow piston-pin, a tube carried by the piston intersecting said pin and extending into the piston chamber, said tube being in communication with the interior of the pin, a stationary tube entering said piston-carried tube, and an annular passage around the latter tube connecting the interior of 25 the wrist-pin with the piston cooling chamber.

10. In an engine cooling system, the combination of a piston having a cooling chamber, a hollow piston-pin, a partition therein 30 defining a circuitous course for the cooling medium, the piston and pin having an opening extending upward therein parallel with the axis of the piston, a stationary upward-projecting tube forming part of the external 35 circulatory system entering said opening, a closed-top tube mounted in the piston receiving the end of the stationary tube and establishing communication between the

same and the interior of the piston-pin at one side of the partition, and a passage between said interior and the piston chamber 40 at the other side of the partition.

11. In a multiple cylinder internal combustion engine having a plurality of cylinders and a plurality of bearings appurtenant 45 respectively to said cylinders, means for circulating liquid in cooling relation to said bearings, and an indicating means in the outflow from the circulation to the bearing pertaining to each cylinder whereby the engineer may determine the relative temperature 50 of the bearings in the engine.

12. In a multicylinder internal combustion engine, a circulatory system for cooling fluid having multiple branches including the piston-pin bearings of the several engine cylinders and a series of indicating means connected in the external portions of said branches adapted to indicate the heat condition of the bearings of the respective 55 cylinders.

13. In an internal combustion engine, the combination with a piston containing a cooling chamber, means for circulating cooling fluid, a piston pin mounted in the piston and having within it a circuitous passage one end of which is in communication with the cooling fluid circulating means and the other with the piston cooling chamber, and means for compelling substantially all the cooling 70 fluid for the piston to pass through the circuitous passage in the piston pin.

In testimony whereof, I have signed this specification.

HUIBERT C. VERHEY.
